ROAD SURFACING PLANE

Walter C. Toaspern, Barryville, N. Y.

Application August 12, 1938, Serial No. 224,456

1 Claim. (Cl. 37—143)

This invention relates to improvements in road and highway surface treating apparatus; and the invention has reference, more particularly, to a novel construction of drag plane adapted for use in scarifying road surfaces, in mixing, distributing and smoothly spreading surfacing materials on road surfaces, and for performing similar work in either the repair of old or the laying of new road surfaces.

This invention has for an object to provide a novel construction of drag plane comprising, a semi-rigid frame upon which are adjustably mounted longitudinally spaced sets of substantially transverse flexible metallic brush blades; the members of said brush blade sets being variously angularly disposed relative to the longitudinal axis of the drag plane in such manner as to cause combined longitudinal and lateral movements of loose material within the width limits of the drag plane, whereby said material is uniformly distributed and smoothly spread over the road surface, and also thoroughly mixed when comprising a plurality of materials, without producing any substantial amount of side spill or the formation of windrows.

This invention has for another object to provide, in a drag plane of the kind described, a novel arrangement of successively spaced brush blade sets, the members of alternate sets being disposed in laterally divergent and laterally convergent relation, whereby loose surfacing material is caused to flow, while also moving longitudinally, alternately outward and inward relative to the longitudinal axis of the drag plane, but in such manner as to be retained within the limits of the width of the latter.

The invention has for a further object to provide, in a road drag plane of the kind mentioned, metallic brush blades formed by rows of suitably spaced steel brush bristle tufts of desired flexibility, thereby to provide and present to the road surface operated upon relatively narrow, semi-rigid, non-clogging cutting edges, while at the same time, owing to the spacing of the bristle tufts, forming a blade structure which will more efficiently both mix and spread loose materials.

Other objects of this invention, not at this time more particularly enumerated, will be understood from the following detailed description of the same.

An illustrative embodiment of my invention is shown in the accompanying drawings, in which:

Fig. 1 is a top plan view of a road drag plane made according to the invention; Fig. 2 is a front

end view of the same; Fig. 3 is a fragmentary transverse sectional view, taken on line 3—3 in Fig. 1, but drawn on an enlarged scale; and Fig. 4 is a fragmentary sectional view, taken on line 4—4 in Fig. 1, but drawn on a further enlarged scale.

Similar characters of reference are employed in the above described views, to indicate corresponding parts.

Referring to said drawings, the novel drag plane comprises a rectangular body frame preferably comprising a plurality of laterally spaced longitudinally extending frame members comprising channel bars 10 disposed with their side flanges 11 upwardly projecting. Said frame members are secured together by cross members 12 which extend across the channel bar ends. Said cross members also preferably comprise channel bars. The intersecting portions of said frame and cross members are suitably fastened together, as by rivets, bolts or like fasteners 13. The body frame thus provided is semi-rigid, i. e. of sufficient flexibility as to assure conformation of the brush blade sets carried thereby to the general contour of the road surface over which the drag plane is operatively drawn.

Secured in desired disposition for projection from the underside of the body frame are a plurality of sets of flexible metallic brush blade members. Each brush blade member comprises a carrier or backing bar 14, the same preferably consisting of a channel bar disposed with its side flanges 15 downwardly projecting. Individually demountably secured to the backing bar 14 between its flanges 15 are rows of spaced metallic tufts 16 affixed in butt sleeves 17, the latter being engaged with and suitably secured to said backing bar 14, so that said bristle tufts depend from the latter. The bristle tuft elements of one row are preferably disposed in suitably staggered relation to those of the other row. The bristles are preferably made of steel strips or wires of suitable length and flexibility. In detail construction per se and in method of attachment to the backing bar 14, said bristle tuft elements preferably correspond in kind to those disclosed in my copending application for United States Letters Patent Serial No. 217,645, filed July 6, 1938.

Said brush blade members are arranged in sets, each set comprising a pair thereof. These sets are disposed in longitudinally spaced apart relation, with the members of alternate sets arranged in laterally divergent and laterally convergent relation. In preferred arrangement, a first set of brush blade members A is affixed to

the forward end portion of the body frame, with its members extending in rearwardly and outwardly inclined angular divergent relation from the inner meeting ends thereof which are aligned 5 substantially with the longitudinal axis of the body frame. The rows of bristle tuft elements carried by the brush blade members A terminate short of the outer side limits of the body frame, thus providing within these limits outlying free 10 material passage spaces A' between the ends of the brush blades formed thereby and the sides of the body frame. The second set of brush blade members B is spaced rearwardly of said first set thereof, and is affixed to the body frame 15 with its members extending in rearwardly and inwardly inclined angular convergent relation from the sides of the body frame toward the center thereof. The rows of bristle tuft elements carried by said brush blade members B extend 20 from points at the sides of the body frame but terminate short of the central portion of the latter so as to provide a central free material passage space B'. The third set of brush blade members C is spaced rearwardly of said second 25 set thereof, and the members thereof are arranged in rearwardly and outwardly inclined divergent relation similar to the described arrangement of the members of set A, and so as to provide outlying free material passage spaces C 30 between the outer ends of their rows of bristle tuft elements and the sides of said body frame. A fourth set D of brush blade elements is affixed across the rearward end portion of the body frame in rearwardly spaced relation to the set 35 C, and is affixed to the body frame with its members extending in shallow angularly convergent relation to meet at the center of the body frame. The rows of bristle tuft elements carried by the members of said set D are of full length, so that 40 together the same extend across the entire width of said body frame.

It will be obvious that the number of sets of brush blade members may be varied and may comprise either more or less than the number 45 thereof above described.

In mounting the brush blade members upon the body frame, the backing bars 14 are disposed back to back relative to the frame bars 10. Means are provided for securing the backing bars 50 14 to the frame bars 10 in such manner that the spaced and angular relations of the former are subject to desired adjustment. A preferred means for this purpose comprises a perforate clip plate 18 disposed to bridge over the upper side 55 of frame bar 10 so as to straddle the point of intersection thereof with a backing bar. Coupler bolts 19 are provided, the same having at their lower ends gripping hooks 20 to engage over the downwardly projecting flanges 15 of said backing bars. The upper threaded end portions of said coupler bolts 19 are passed through the perforations of said clip plate 18, being thereupon adapted to receive fastening nuts 21, which, when screwed home, draws the intersecting portions 60 of the frame bar and backing bar into strongly clamped together relation (see Fig. 4).

Suitable means are provided at the forward end of the drag plane for drawing the same over a road surface to be treated. This means may 70 include eye-bolts 22 affixed to the front cross bar 12, to which draft chains 23 or the like may be connected.

When using the novel drag plane for scarifying pitted surfaces of old roads, the same is dragged 75 over the road surface, by horse, tractor or like

operating power, so that the brush blades contact with and work upon the road surface material. As the plane advances over the road surface, the multiplicity of flexible steel bristle tufts act upon the surface with scarifying effect operative 5 to cut down the high spots and thereupon distribute the loosened material over the surface so as to fill the same into the low spots, and thus bring the road surface to a normal and substantially uniformly leveled condition. Due to the 10 novel arrangement of the brush blades in successive sets of alternately divergently and convergently disposed members which are further arranged to provide, at the ends of respective sets, outer and inner material clearance spaces leading 15 from one set to the other, and disposed within the lateral limits of the body frame, the loosened material is caused to partake of a combined lateral and longitudinal movement within the width limits of the area of the body frame. This 20 results in a highly efficient distributive spreading and leveling of the loosened material, without side spill outwardly of the body frame or the formation of windrows which must either be collected or subsequently spread to the detriment of 25 uniform leveling of the road surface. In the operation, as thus carried on, the first set of brush blades A, in producing and working over the loosened material by the action of the flexible bristle tufts, permits some of the material to work 30 through the spaces between said bristle tufts, while other portions thereof are moved more or less laterally outward along the divergently inclined brush blades so as to spill through the outer spaces A' to discharge in the path of movement of the succeeding convergently inclined brush blades B. Again the material is worked by the bristle tufts of said brush blades B, together with additional material loosened by the 35 action thereof, so as to work through and between the same, while the excess is moved more or less laterally inward along the same to spill through the inner space B' for discharge in the path of movement of the next succeeding divergently inclined brush blades C, being in similar 40 manner worked by the latter, and finally discharged in the path of the last set of brush blades D which, since they extend across the entire width of the plane, operate to produce a final leveling distribution of the material. By this 45 novel action the loose material is quickly deposited where needed in required quantity, while at the same time the excess is evenly distributed and spread over the road surface, so as to provide the desired uniformly leveled road surface 50 condition.

By reason of the unique arrangement of the brush blade sets, and due to the flexibility of the steel bristle tufts making up the same, it is possible, by use of the novel drag plane, to economically and practically effect repairs to road surfaces where it is undesirable to break the existing bond, as e. g. in connection with water bound macadam, oiled surface treatment, stabilized soil surfaces, stone base roads, etc. When 55 working on such surfaces, the drag plane will, without damaging the surface, completely and uniformly effect the distribution of stone, stone and oil or miscellaneous repair material in a most efficient manner. For example, when it is 60 desired to apply a top dressing of fine stone, gravel or the like together with oil or a bituminous binder, such material may be roughly spread upon the road surface and thereupon worked by moving the novel drag plane there- 65 70 75

over. The operation of the drag plane thereupon will not only effect a smooth or evenly leveled distribution of the surfacing material, but by the action of the brush blade members in causing combined longitudinal and lateral movements of the stone or gravel, the stone or gravel particles will be rolled or turned over and over in the presence of the oil or bituminous binder so as to be thoroughly coated by the latter, and consequently when finally spread and brought to rest will be more firmly and efficiently bound together and to the road body so as to form a desired new or repair top dressing.

The novel brush blade elements, comprising rows of metallic bristle tufts of desired flexibility, provide semi-rigid, non-clogging cutting means for operative presentation to the road surface so as to effect a highly efficient scarifying action, the intensity of which may be varied by substituting heavier or lighter tuft units. The tuft units being individually replaceable relative to the backing members makes repair of the brush blades a very quickly and easily accomplished task.

I am aware that various changes could be made in the above described constructions, and many apparently widely different embodiments of the invention could be made without departing from the scope thereof as defined by the following claim. It is therefore intended that all matter contained in the above description or shown in the accompanying drawings shall be interpreted as illustrative and not in a limiting sense.

I claim:
A drag plane for the purposes described, com-

prising a body frame formed by pairs of longitudinally extending laterally spaced frame bars disposed at opposite sides of its central longitudinal axis, and cross bars joining said frame bars at the ends thereof to provide a flexible structure, a plurality of brush blade members carried by each pair of longitudinal frame bars, each blade member comprising a backing bar having rows of metallic bristle tuft units affixed thereto for downward projection therefrom, means to adjustably affix said brush blade members respectively to and bridging across the members of said pairs of frame bars with their backing bars arranged back to back with the latter, said brush blade members as thus carried being arranged to provide successively spaced transverse sets disposed between the front and rear ends of the body frame, the members of alternate sets being angularly disposed in relatively divergent and convergent relation, and so as to respectively provide within the width of said body frame outer and inner material spill spaces to discharge loose material from an advance set into the path of the brush blades of a succeeding set, whereby said material is caused to move longitudinally and laterally within the side limits of the body frame and without appreciable side spill exteriorly of the latter, a first set moving the material outwardly, a second set moving the material inwardly, a third set again moving the material outwardly, the members of said respective sets being disposed in acute angular relation, and a final set for moving the material inwardly, the members of said final set being disposed in obtuse convergent angular relation.

WALTER C. TOASPERN.
